UNITED STATES PATENT OFFICE.

OSCAR C. TRAUTMAN, OF LAKewood, OHIO.

ELECTRIC HEATING ELEMENT.

Application filed April 2, 1924. Serial No. 703,849.

To all whom it may concern:

Be it known that I, OSCAR C. TRAUTMAN, a citizen of the United States of America, and a resident of Lakewood, in the county 5 of Cuyahoga and State of Ohio, have invented certain new and useful Improvements in Electric Heating Elements, of which the following is a full, clear, and exact description.

10 This invention relates to electric furnaces and has for its object the provision of an improved structure for supporting the electric resistance elements. It is well known that these elements are sometimes pushed to a 15 high degree of temperature which is injurious to the surroundings both by reason of such temperature and of the expansion produced thereby; and it is also well known that nearly all the substances which are 20 both electrically resistant and sufficiently refractory to be employed as supports and housings at such temperatures are also brittle, non-metallic substances which are impossible to be fashioned into complicated or 25 intricate shapes and which cannot easily be worked into any shape but must be capable of immediate molding. The objects of my invention are the provision of a resistor support of such character that both the resistor 30 and the support can be readily formed out of material customarily used for the purpose and shall enable free expansion and contraction relative to each other; the provision of a support which can readily be molded out 35 of customary refractory substances and which shall be free from intricate or difficult shapes and possess a maximum of strength both hot and cold; while other objects and advantages of the invention will become apparent as the description proceeds.

In the drawings accompanying and forming a part of this application Fig. 1 is a side elevation of a resistance element embodying my improvements; Fig. 2 is a section on the line 2-2 of Fig. 1; Fig. 3 is a horizontal section on the line 3-3 of Fig. 1; Fig. 4 is a side elevation showing a slightly different design of support; Fig. 5 is a sectional view of the parts shown in Fig. 4; Fig. 6 is a sectional view of another type of element; Fig. 7 illustrates one mode of mounting the last named element in a furnace; Fig. 8 illustrates a mode of mounting the first described type of element; and Fig. 55 9 is a horizontal sectional view corresponding to the line 9-9 of Fig. 6.

In Figs. 1 to 3 of the drawings I have shown an elongated narrow plate 1 of any suitable refractory material such as alumina or carborundum combined with a suitable binder, having slots therein for the reception of supporting blocks which are preferably made of substantially the same refractory material. I have shown two slot arrangements, namely a row of open slots 3-3 along one edge and a row of keyhole slots 4-4 at a distance therefrom. It will be understood that either set of slots could under certain conditions be used to the exclusion of the other set, although preferably I employ both sets in cooperation to secure the resistor element in place. Located in the open slots 3 are suitable blocks 5 here shown as H-shaped, the width of each block being such as to fit snugly in its slot, and the notch 6 which is formed at one side of the block being of a width to receive snugly the body of the plate. The slot 7 at the opposite side of the block is preferably made of a sufficiently greater width to receive between it and the face of the plate the resistor element hereafter described. The depth of the notch 3 and the width of the block are subject to considerable variation as it is immaterial to the operation of the device whether the resistors are supported below the edge of the plate as shown in Fig. 2 or project above the same as shown in Fig. 5; provided only that a suitable head or heads be provided for the secure reception of the resistors. In Figs. 2 and 5 I have shown resistors located at both sides of the plate, the notch 7 being made of sufficient width for this purpose or formed with a head at each end, but my improvement equally comprehends the employment of only a single resistor as shown in Figs. 6 and 7 for which purpose the blocks 5^a are shortened and the notches 7^a narrowed accordingly.

For the keyhole slots 4 I have shown other blocks 10, likewise of H-shape, the body portions 11 being of a size and shape to fit snugly the narrow portion of the slot and the heads 12 being arranged to overlie the faces of the plate 1 adjacent thereto. In case a resistor is to be mounted at each side of the plate as shown in Figs. 2, 3, 5, and 8 the length of each block 10 between the heads is made sufficient to receive such elements at each side. If a resistor is to be employed at only one side of the plate as shown in Figs. 6, 7, and 9 the blocks are shortened

so that the heads 12^a engage the plate directly the opposite head is being spaced therefrom sufficiently to receive the single resistor.

In the preferred arrangement I form the resistor of a metal rod 15 bent or cast in sinuous shape forming a flat zigzag coil adapted to lie snugly against the face of the plate. I have shown the upper loops of this resistor as suspended over the blocks 5 and 10 the depending legs of the same as passing adjacent to the keyhole slots 4 in such wise as to be overlapped by the heads 12, the combined action of the two sets of blocks holding the resistor firmly in place while 15 permitting free expansion and contraction and enabling ready emission of heat. It is immaterial whether the keyhole slots and open slots, when both are employed, are in line with each other or not. In Fig. 1 I 20 have shown them as staggered in which case the blocks 10 are located inside the depending loops; in Fig. 4 I have shown them as located in line with each other wherefore the blocks 10 lie between adjacent loops. In 25 case resistor elements are used at both sides of the plate, the two may be connected by means of a horizontal loop 16 embracing one end of the plate, but any suitable design of connection may be employed.

In order to support my improved elements I preferably employ suitable blocks or slabs of refractory material, such for example as that employed in the plates and blocks already described, the upper edges 30 of the last named blocks or slabs being notched for the reception of the plates which are thereby supported in a substantial upright position. The number of notches employed in the supporting block 35 will depend upon the number of resistor elements employed, and the width of those notches will depend upon the mode of applying such elements thereto. In Fig. 7 I have shown a supporting block 20 as inset 40 in the side wall 21 of a furnace, said block being formed at its upper edge with a single slot 22 of a width to receive the plate 1 very snugly. The block 20 being located so as to come between successive depending 45 legs of the resistor 15. In Fig. 8 I have shown an elongated slab 23 formed in its upper edge with a plurality of spaced slots 24 adapted for the reception of plural plates 1 whereby a battery of these devices 50 are supported near each other for concentrated heating. In this case I have shown the slots 24 of a sufficient width to receive the plates together with their resistors.

It will be understood that many changes 55 in detail can be made within the scope of my inventive idea; the most important feature of my invention consists of the employment of supporting devices of simple contour interfitting by the use of simple notches, thereby enabling the production of

these parts from plastic refractory materials with a maximum of ease, and avoiding complicated and fragile parts which are liable to become broken under the severe physical conditions to which they are subjected, while at the same time permitting the necessary relative expansion and contraction of the parts. It is not material as to the number or arrangement of these slots or the number or arrangement or shape of the resistors nor the number of plates and elements employed either in line or side by side, wherefore I do not limit myself except as specifically set forth in my several claims.

Having thus described my invention what I claim is:

1. A resistor support comprising a refractory plate having slots, and blocks of refractory material having slots to interfit with said first slots in dovetailed relation and heads to receive the resistors.

2. A resistor support comprising an elongated plate of refractory material having slots therein from side to side, and blocks of refractory material adapted to fit in said slots and also having slots adapted to receive portions of said plate adjacent to said slots said blocks also having heads to hold the resistors.

3. A resistor support comprising a unitary elongated plate of refractory material having slots at one edge, and blocks of refractory material adapted to fit in said slots and having heads to hold the resistors.

4. A resistor support comprising an elongated plate of refractory material having slots at one edge, and blocks of refractory material adapted to fit in said slots and also having slots adapted to receive said plate, said slots being so arranged that the plate 105 and blocks are mutually dovetailed together, said blocks also having heads to hold the resistor elements.

5. A resistor support comprising an elongated plate of refractory material having keyhole slots therein and blocks of refractory material having enlarged ends to pass through the larger parts of said slots and reduced bodies to fit the narrow parts of said slots, certain enlarged ends constituting 110 attachments for resistors.

6. A resistor support comprising an elongated plate of refractory material having slots at one edge, and blocks of refractory material adapted to fit in said slots, said plate also having keyhole slots at a distance 115 from said first slots and other refractory blocks adapted to fit said keyhole slots, all said blocks having slots adapted to dovetail with said plate and also having heads 120 adapted to engage and hold the resistors.

7. A resistor support comprising an elongated plate of refractory material having slots at one edge and keyhole slots in its body, and H-shaped blocks of refractory ma- 125

terial adapted to interfit with said slots and to engage the resistor.

8. A resistor support comprising a refractory plate having slots, blocks of refractory material interlocked with said slots and supporting a resistor, and a supporting block of refractory material positioned crosswise of said plate and having an upwardly opening slot receiving said plate.

10. An electric resistance heating element comprising a refractory plate having slots therein, a sinuous looped conductor located adjacent the face of said plate with a loop adjacent each slot, and a block of refractory material interlocked with each slot and having a head engaging the adjacent loop, each block being slotted for dovetailed engagement with said plate.

10. An electric resistance heating element comprising a narrow refractory plate having spaced open slots at one edge and similarly spaced keyhole slots near the other edge, means supporting said plate edgewise with said open slots uppermost, refractory blocks in said slots and fitted thereto and

overlapping a part of the bar adjacent thereto, said blocks having heads spaced from the face of the plate, and a sinuous looped resistor engaging said heads.

11. A resistor support for electric heating elements comprising a narrow refractory plate having slots therein from side to side, and refractory blocks fitting in said slots and overlapping a part of the plate adjacent thereto on both faces, said blocks having heads adapted to receive a resistor.

12. An electric furnace comprising the combination with a refractory shell of a refractory block therein having an upwardly opening slot, a refractory plate mounted edgewise in said slot and itself having slots extending from side to side, refractory blocks fitting in said last slots and themselves also slotted to dovetail with the plate, and resistors carried by said blocks and lying alongside the face of said plate.

In testimony whereof, I hereunto affix my signature.

OSCAR C. TRAUTMAN.
